UNITED STATES PATENT OFFICE.

EDWARD J. N. STENT, OF BERGEN POINT, NEW JERSEY, ASSIGNOR TO COOK
& BERNHEIMER, OF NEW YORK, N. Y.

DESIGN FOR A BOTTLE.

SPECIFICATION forming part of Design No. 19,725, dated March 25, 1890.

Application filed February 15, 1890. Serial No. 340,630. Term of patent 14 years.

To all whom it may concern:

Be it known that I, EDWARD J. N. STENT, a citizen of the United States, residing at Bergen Point, New Jersey, have invented and produced a new and original Design for Bottles, of which the following is a specification, reference being had to the accompanying drawings, forming a part thereof.

Figure 1 is an edge view of a bottle showing my design. Fig. 2 is a side view of the same. Fig. 3 is a top view.

The leading feature of my design consists in a body portion in the form of a parallelopiped, the sides of which appear about square and the ends oblong. A neck projects from the top of the body. The neck curves out-

ward at its bottom, and this curve dies partly into the sides of the body and partly into the top of the body, leaving horizontal shoulders on two sides of the neck adjacent the ends ²⁰ of the body. The sides and ends of the body are plane and the corners are slightly rounded.

The sides in the drawings are lettered *a*, the ends *b*, the bottom *c*, the top *d*, and the neck *e*.

I claim—

The design for a bottle herein shown and described.

EDW. J. N. STENT.
